UNITED STATES PATENT OFFICE

BERT G. LARRABEE, OF HOUSTON, TEXAS

DESIGN FOR A BOWL

Application filed July 23, 1931. Serial No. 40,846. Term of patent 7 years.

To all whom it may concern:

Be it known that I, BERT G. LARRABEE, a citizen of the United States, residing at Houston, in the county of Harris and State of Texas, have invented a new, original, and ornamental Design for a Bowl, reference being had to the accompanying drawings, forming a part hereof.

Fig. 1 is a perspective view of a bowl showing my new design; Fig. 2, a side elevation thereof; and Fig. 3, a top plan view thereof.

I claim:

The ornamental design for a bowl, as shown.

In testimony whereof, I hereunto affix my signature.

BERT G. LARRABEE.
